UNITED STATES PATENT OFFICE

HARRY YOUNG, OF MELBOURNE, KENTUCKY

DESIGN FOR A RADIATOR ORNAMENT

Application filed June 13, 1931. Serial No. 40,187. Term of patent 7 years.

To all whom it may concern:

Be it known that I, HARRY YOUNG, a citizen of the United States, residing at Melbourne, in the county of Campbell and State of Kentucky, have invented a new, original, and ornamental Design for Radiator Ornaments, of which the following is a specification, reference being had to the accompanying drawings, forming part thereof.

Figure 1 is a front view of a radiator ornament showing my new design.

Figure 2 is a top plan view thereof; and

Figure 3 is a cross section on the line 3—3 of Figure 1.

I claim:

The ornamental design for a radiator ornament as shown.

HARRY YOUNG.
